Nathaniel Waterman of Boston, Mass
Letters Patent No. 1007. Dated May 25th 1858.

The schedule referred to in these Letters Patent and making part of the same.

To all persons to whom these presents shall come:—

Be it Known that I Nathaniel Waterman of Boston in the County of Suffolk, and State of Massachusetts, have invented or produced a new ornamental design or configuration for a Towel Stand, and do hereby declare that the same is fully represented in the accompanying drawings, of which.

Figure 1. is a perspective view of a Towel Stand made in accord-

ance with my invention.

Figure 4. is a side view of one of the end standards of the Towel Stand.

The peculiar arrangement of the curves of the branches, a, a, and the feet, b, b, of the leg or post, c, as shown in Figure 1, of the drawings, when taken together and in connection with the straight leg, c, completes the design.

I claim such design as represented and described.
